ADJUSTABLE RESILIENT SEAT

Albert F. Raders, Freeport, Ill.

Application August 20, 1937, Serial No. 160,163

1 Claim. (Cl. 155—52)

This invention relates broadly to seats and more particularly to an improved seat or stool designed and intended particularly for use by engineers and firemen in cabs of railroad locomotives.

An object of the present invention is to provide a seat of the character above mentioned that is both resilient and adjustable vertically to the desired height.

10 The invention together with its objects and advantages will be best understood from a study of the following description taken in connection with the accompanying drawings wherein:

15 Figure 1 is a side elevational view of the seat, a raised position of the seat being indicated by broken lines.

Figure 2 is a rear elevational view of the seat.

Figure 3 is a sectional view through the seat showing the adjustable support therefor.

20 Figure 4 is a perspective view of a foot rest.

Figure 5 is a perspective view of a cylinder or tube hereinafter more fully referred to.

Figure 6 is a top plan view of the seat proper with the seat cushion removed.

25 Figure 7 is a bottom plan view of the seat cushion.

Figure 8 is a perspective view of a floor plate, and

30 Figure 9 is a perspective view of the vertically shiftable section of the seat.

Referring to the drawings by reference numerals it will be seen that in the preferred embodiment thereof the seat comprises a pair of front and rear floor plates 5 respectively provided at 35 their respective opposite ends with apertures 6 for the reception of screws or similar fastening devices through the medium of which the plates 5 are secured to the floor of a locomotive cab.

Each of the plates 5 have rising therefrom, and 40 inwardly from the ends thereof, standards 7.

Supported by the standards 7 for vertical sliding movement is a skeleton box-like frame structure indicated generally by the reference numeral 8.

45 As shown in Figure 9 the frame structure 8 comprises a plate 9 from the corners of which rise tubular members 10 that have a sliding fit with the standards or posts 7. At their upper ends the tubular members 10 have welded or otherwise 50 secured thereto corner portions of a frame 11.

At the front and rear thereof plate 9 is provided with depending flanges 12 complementary to lugs or flanges 13 that extend upwardly from the floor plates 5.

55 For raising and lowering the frame structure

8, and for securing the latter at the desired elevation, there is provided an adjustable support consisting of coacting pairs of toggle links 14 and 15.

The links 14 are pivoted to the lugs or flanges 12 as at 16 while the links 15 are pivoted to the lugs or flanges 13 as at 17.

The links 14 and 15 are pivotally connected by pivots 18 and 19.

The pivots 19 are provided on the respective 10 opposite ends of a cross bar 20 while connected to the pivots 18 are the angular ends of a cross bar 21.

An adjusting screw 22 has a threaded end 23 15 threadedly engaged with an intermediate portion of the bar 20 and a second end journaled in a suitable opening provided therefor intermediate the ends of the bar 21. Screw 22 is secured against longitudinal movement through the medium of collars 24 provided thereon at opposite sides of 20 the bar 21.

An on the collar-equipped end thereof screw 22 15 is also provided with a ratchet wheel 25 and a lever 26 has one end connected with the screw 22 to rotate about the latter as an axis.

25 Lever 26 is equipped with a detent structure 27 cooperable with the ratchet 25 so that obviously by oscillating the lever 26 movement of the lever through the medium of the detent 27 and rack wheel 25 will be transmitted to the screw 22 30 for turning the latter to cause the bar 21 to feed longitudinally of the threaded end of the screw for raising or lowering, as the case may be, the frame structure 8 and consequently the seat proper carried thereby. The seat proper indicated generally by the reference numeral 28 consists of a plurality, in the present instance, three laterally spaced straps 29 which at one end are upturned as at 30 to provide back rest extensions for supporting an upholstered back rest 31.

35 The straps 29 are secured in laterally spaced relation through the medium of front and rear cross straps or bars 32.

The bars 32 are secured to the straps 29 through the medium of the upper ends of rods 33 that extend through apertures in the members 29 and cross bars 32 that have threaded thereon upper and lower nuts 34, 35.

40 A cushion for the bottom of the seat is indicated by the reference numeral 36, and on the underside thereof the cushion 36 is provided with angular elements 37 as shown in Figure 7 that engage the nuts 34 associated with the endmost rods 33 in a manner to secure the cushion 36 45 against lateral displacement.

50

The rods 33 work through openings 38 provided therefor in the front and rear ends of the frame element 11 and are received in the upper ends of tubes or cylinders 39. Cylinders 39 are secured in vertical position on the plate 9 at the front and rear edges of the plate through the medium of bolts and nut means 40.

Adjacent the lower ends thereof the rods 33 are provided with lateral pins 41 that are accommodated in longitudinal slots 42 provided in the tubes or cylinders 39.

Washers 43 have a sliding fit on the tubes or cylinders 39 and are engaged by the pins 41 as clearly shown in Figure 2.

Disposed about the tubes or cylinders 39 are coil springs 44 that at their lower ends impinge against the plates 9 and at their upper ends impinge against the washers 43.

It will thus be seen that a resilient support for 20 the seat 28, in addition to the adjustable support for the seat, is provided.

Also in accordance with the present invention there is provided a foot rest 45 having at the opposite ends thereof rearwardly extending arms 46. At the free ends thereof arms 46 are pivoted as at 50 to eyes or sleeves 47 sleeved on the front posts or standards 7 whereby the rest 45 is mounted for vertical adjustment. Sleeves 47 are provided with stops 51 to support the foot rest in horizontal position.

At the sleeve-equipped ends thereof arms 46 are provided with laterally extending lugs 48. Lugs 48 are equipped with threaded apertures to accommodate adjusting screws 49, the lower ends of which bear on the front or forwardmost floor plate 5 at the ends of the latter. It will thus be seen that to raise or lower the foot rest 45 as found desirable screws 49 are turned causing the lugs 48 to feed vertically thereon and in the proper direction to raise or lower the foot rest 45.

When not used foot rest 45 may be swung up-

wardly to a substantially vertical out-of-the-way position.

From the above it will be seen that I have provided an adjustable resilient seat which may be used wherever a seat of such a character is desired, and which will especially be found desirable for use in a locomotive cab.

It is thought that a clear understanding of the construction, utility and advantages of an invention of this character will be had without 10 a more detailed description.

Having thus described the invention what is claimed as new is:

In a seat of the class described, a frame including a lower plate, a rectangular-shaped upper 15 member, uprights connecting the plate and member together, said plate and rectangular-shaped member having a row of spaced holes adjacent each end thereof, the holes in the plate being aligned with the holes in the member, tubular 20 members, bolts connected at the lower ends of the tubular members and passing through the holes in the plate, nuts engaging said bolts for holding the same in the holes of the plate, two rows of vertically arranged rods passing through 25 the holes in the rectangular member and into the tubular members, a strap connecting the upper end of each rod of one row with a corresponding rod of the other row, said straps being connected with the upper ends of the rods, each 30 tubular member having a longitudinally extending slot therein, a pin carried by each rod and engaging the slot therein, a washer slidably arranged on each tubular member located under the pin and a coil spring surrounding each tubular member and having one end bearing against the bottom plate and its other end engaging the washer and a strap connecting the upper ends of each row of rods together.

ALBERT F. RADERS.
